GUARD DEVICE FOR MOVING STRUCTURES

Robert S. Quinn, Steubenville, Ohio

Application November 27, 1933, Serial No. 699,987

5 Claims.

(Cl. 212—70)

This invention relates to guard devices, and more particularly to guard devices for moving structures, such as locomotive cranes, although not limited thereto.

5 In the operation of locomotive cranes, for example, a very dangerous hazard is created for men standing beside the crane truck at the time the cab of the crane is rotating. The unguarded cab is liable to crush the workmen 10 against the side of the crane truck, and serious injuries often result.

One object of the invention is the provision of a novel guard for moving structures which operates in such manner as to automatically push aside men caught by chance in a danger zone, and thus preclude the possibility of their injury.

Another object is to provide a novel construction of the class described which will be automatically placed in operative position and likewise automatically removed therefrom when its use is unnecessary, thereby resulting in flush clearances with the moving structure.

These and other objects will be apparent after referring to the drawings, in which:

Figure 1 is a plan of a typical locomotive crane, and showing the crane arm broken away.

Figure 2 is a plan similar to Figure 1, but disclosing the function of the novel device of 30 the invention.

Figure 3 is a plan of the elements of the device of the invention as applied to the locomotive crane.

Figure 4 is a fragmentary elevation.

Figure 5 is an enlarged elevation.

Figure 6 is a sectional detail.

Figure 7 is a plan similar to that of Figure 3, but disclosing the device in one of its stages of 40 operation.

Referring more particularly to the drawings, the letter A designates a conventional railway truck, which is adapted for movement on the tracks B and serves to carry a crane cab C. The crane cab C has connected to one of its 45 ends the usual crane arm D.

A pair of segmental racks 2 are secured to the truck A as by means of bolts 3. A pair of curved guards 4 are pivoted to the under side of the crane cab C, as at 5, and adapted for swinging movement toward and away therefrom. A boss 6 is vertically mounted on the under side of the crane cab C and carries on one of its ends a gear 7 which is provided with a retaining plate 8, the latter being held in position by 50 means of bolts 9.

The boss 6 has an eccentric 10 connected to its other end. A link 12 is connected to one of the guards 4 and to the lobe 10^a of the eccentric, as shown at 13 and 14, respectively. Another link 15 is connected to the other of the guards 4 and to a centrally offset position on the gear 7, as shown at 16 and 17, respectively. The free end of each of the guards 4 is provided with a bearing block 18 which is adapted for movement in an individual guide 19, the latter being secured to the under side of the crane cab C by means of capscrews 20.

In operation, the locomotive crane cab C is made to rotate in the conventional manner, and causes the gear 7 to mesh with one of the segmental racks 2, dependent, of course, upon the direction of rotation.

This movement causes the lobe 10^a of the eccentric and the offset pivotal point 17 on the gear 7 to extend the links 12 and 15, which accordingly act to swing the guards 4 away from the side of the crane cab. The advanced position of the curved guards with respect to the side of the crane cab serve to ward off workmen standing in the zone of danger, which is at, or adjacent, the position represented in the drawings at X.

As the crane cab C continues to rotate, the gear 7 will move out of contact with its initially cooperating rack 2, and remain stationary until it engages the other rack. Cooperation with the last mentioned rack causes the gear 7 to rotate further and retract the extended guards 4 to inoperative positions, entirely under the crane cab, providing "flush clearances" on either side thereof, which is highly essential when the crane is not operating.

It will thus be seen that whenever the crane cab is positioned with its crane arm D extending longitudinally with respect to the truck A, the curved guards 4 will remain retracted, but will immediately move into operative position if the crane cab is rotated in either direction.

While I have shown and described one specific embodiment of my invention, it will be understood that I do not wish to be limited exactly thereto, since various modifications may be made without departing from the scope of my invention, as defined in the following claims.

I claim:

1. A guard device for moving structures, comprising at least one guard member pivoted to said moving structure, a shaft journaled on said moving structure and carrying a gear and an eccentric, a link connecting said guard member 110

- and said eccentric, and a stationary rack with which said gear is adapted to mesh.
2. In combination with a moving structure, a support for said structure, at least one rack on 5 said support, a shaft journaled on said moving structure and carrying a gear for engagement with said rack, an eccentric mounted on said shaft, at least one guard member pivoted to said moving structure adjacent the area to be protected, and a link connecting said eccentric and 10 said guard member.
3. In combination with a moving structure, a support for said structure, at least one rack on said support, a shaft journaled on said moving 15 structure and carrying a gear for engagement with said rack, an eccentric mounted on said shaft, at least one guard member pivoted to said moving structure adjacent the area to be protected, a link connecting said eccentric and 20 said guard member, and a guideway for said guard member.

4. In combination with a locomotive crane, a pair of curved racks secured to the truck therefor, a shaft journaled on said crane and carrying a gear for temporary engagement with each of said racks, an eccentric mounted on said shaft, a pair of guard members pivoted on one of their ends to said crane, and a link connecting each of said guard members to said eccentric. 80
5. In combination with a locomotive crane, a pair of curved racks secured to the truck therefor, a shaft journaled on said crane and carrying a gear for temporary engagement with each of said racks, an eccentric mounted on said shaft, a pair of guard members pivoted on one of their ends to said crane, a guideway for the other end of each of said guards, and a link connecting each of said guard members to said eccentric. 85
